(57) **CLAIM**

The ornamental design for a charger as shown and described.

DESCRIPTION

FIG. 1 is a top, left side isometric view of our new design for a charger.

FIG. 2 is a top side plan view of FIG. 1.

FIG. 3 is a bottom side plan view of FIG. 1.

FIG. 4 is a left side elevation view of FIG. 1.

FIG. 5 is a right side elevation view of FIG. 1.

FIG. 6 is a front side elevation view of FIG. 1.

FIG. 7 is a back side elevation view of FIG. 1.

FIG. 8 is an isometric view of the charger of FIG. 1 with the body of a smart watch attached for charging.

FIG. 9 is a top, left side isometric view of our new design for a charger, all other surfaces being the same as the embodiment of FIG. 1 other than the disclaimed surfaces.

FIG. 10 is a top side plan view of FIG. 9.

FIG. 11 is a bottom side plan view of FIG. 9.

FIG. 12 is a left side elevation view of FIG. 9.

FIG. 13 is a right side elevation view of FIG. 9.

FIG. 14 is a front side elevation view of FIG. 9.

FIG. 15 is a back side elevation view of FIG. 9; and,

FIG. 16 is an isometric view of the charger of FIG. 9 with the body of a smart watch attached for charging.

Contour is shown with line shading; no difference in color, texture or material is claimed unless expressly noted. The line shading represents contour, not surface decoration. The features shown in broken lines in the drawings depict environmental structure and portions of the charger that form no part of the claimed design. The dash dot dash broken lines shown in FIGS. 9 and 14 define the bounds of the claimed design and form no part thereof.
